United States Patent Office

Des. 229,578

Patented Dec. 11, 1973

229,578

HORIZONTAL COLLET FIXTURE

Orlando Milet, Four Mile Point Road,
Athens, N.Y. 12015

Filed May 3, 1971, Ser. No. 140,023

Term of patent 14 years

Int. Cl. D15—99

U.S. Cl. D54—4

FIG. 1.

FIG. 2.

FIG. 1 is a perspective view of a horizontal collet fixture embodying my new design; and

FIG. 2 is a perspective view thereof taken from the opposite side of FIG. 1.

The best description of the design is as is illustrated by the drawing figures.

I claim:

The ornamental design for a horizontal collet fixture, as shown.
